UNITED STATES PATENT OFFICE.

FRED QUANDT, JR., OF FORT MORGAN, COLORADO, ASSIGNOR OF ONE-HALF TO WILLIAM KUHRT, OF FORT MORGAN, COLORADO.

AIR PUMP.

Application filed July 25, 1927. Serial No. 208,343.

This invention relates to an air pump, the general object of the invention being to provide means whereby the pump can be used either as a double action pump or a single action pump.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:

Figure 1 is a longitudinal sectional view.

Figure 2 is a section on line 2—2 of Figure 1.

20 In these views 1 indicates the cylinder of the pump which has its upper end closed by a cap 2 which carries the gland 3 for the piston rod 4. The inner end of the rod carries the two pistons 5 and 5', the piston 5 acting to 25 compress the air in the cylinder on the up stroke of the pump and the piston 5' acting to compress the air on the down stroke. Ports 6 and 7 are formed in the cap 2 and a nipple 8 is screwed into the enlarged outer end of the 30 port 6, this nipple having a port 9 therein so that air can pass through the nipple and the port 6 to the upper part of the cylinder on the down stroke of the piston. The inner end of the nipple has a valve seat which is 35 adapted to be engaged by the valve 10 which is forced upon the seat by the pressure of air created in the cylinder on the up stroke of the piston 5, this air passing through the port 7 into the coupling 11 to which is connected the tube 12 which leads the air to the point of use. A ball valve 13, limited in its movement by a coil spring 14, prevents air being drawn through the port 7 on the down stroke of the 40 piston 5.

45 An upright tube 15 has one end inserted in an opening in a short tube 15' which is inserted in an opening at the lower end of the cylinder. A port 16 is formed in the tube 15, adjacent its upper end, and the tube 15' 50 has a valve seat in its inner end for a ball valve 17 and a spring 19 normally holds the valve on its seat, though said valve will move off its seat and permit air to enter the lower part of the cylinder through the tubes 15 and 15' on the upward stroke of the piston 55

5'. The air compressed in the lower part of the cylinder by the piston 5' on its down stroke will pass through the nipple 20 and the pipe 21 which has its upper end connected with the coupling 11 and a ball valve 22 in 60 a nipple 23 which is screwed in the coupling and with which the upper end of the tube 21 connects, prevents air being drawn into the tube 21 on the up stroke of the piston 5'.

The nipple 8 is closed by a threaded plug 65 24 and a rod 25 passes through the plug into the nipple and has a collar 26 thereon within the nipple. A coil spring 27 is arranged on the rod and bears against the collar 26 and tends to hold the rod in a position where it 70 will hold the valve 10 off its seat. A knob 28 is connected with the outer end of the rod and a cross pin 29 passes through the rod. The outer end of the plug is provided with a groove 30 to receive the cross pin and when 75 the pin is in said groove, the spring will hold the rod in a position where it will force the valve 10 off its seat. When the rod is turned to a position where the pin will not engage the groove, then the rod is held in a position 80 where the valve 10 can engage its seat. When the valve 10 again engages its seat, the pump will act as a double action pump, but when the valve is held off its seat by the rod 25, the pump will act as a single action pump. 85

On the down stroke, the air will enter through the port 6, the port 7 being closed, while the air previously drawn into the lower part of the pump by the upwardly moving piston 5' will be forced from the cylinder 90 through the pipe 21, past the valve 22 into the coupling 11, from which it will pass through the pipe 12. Then on the upward stroke, the air in the upper part of the cylinder will pass through the port 7 into the 95 coupling 11 and pipe 12, while air is being drawn into the lower part of the cylinder through the pipe 15. When the device is used as a single action pump, the air will be drawn in and exhausted through the port 6, 100 as the valve 10 remains off its seat at all times.

It is thought from the foregoing description that the advantages and novel features of my invention will be readily apparent. 105

I desire it to be understood that I may make changes in the construction and in the combination and arrangement of the several parts, provided that such changes fall within the scope of the appended claim. 110

What I claim is:—

A pump of the class described comprising a cylinder having an inlet and exhaust port at each end thereof, an L-shaped tubular member connected with the lower end of the cylinder and in communication with the inlet port at the lower end of the cylinder, the upper end of the member being closed and having a port therein adjacent its upper end, 5 a spring pressed valve for controlling said inlet port, a double piston in the cylinder, a piston rod connected therewith and passing through the top of the cylinder, an inwardly opening valve controlling the inlet port at 10 the upper end of the cylinder, a T-coupling 15

connected with the outlet port at the upper end of the cylinder, an outwardly opening spring pressed valve in said coupling for controlling the outlet port, a tubular member connecting the coupling with the outlet port at the lower end of the cylinder, an upwardly opening valve controlling the passage 20 between the tubular member and the T-coupling, a spring-pressed rod for forcing the inlet valve at the upper end of the cylinder off its seat and means for holding the rod in retracted position to permit the inlet valve to engage its seat. 25

In testimony whereof I affix my signature.

FRED QUANDT, JR.
